UNITED STATES PATENT OFFICE.

DAVID S. JACOBUS, OF JERSEY CITY, NEW JERSEY, ASSIGNEE TO THE BABCOCK & WILCOX COMPANY, OF BAYONNE, NEW JERSEY, A CORPORATION OF NEW JERSEY.

WATER-TUBE BOILER.

1,134,077.

Specification of Letters Patent. Patented Mar. 30, 1915.

Application filed September 21, 1912. Serial No. 721,530.

To all whom it may concern:

Be it known that I, DAVID S. JACOBUS, a citizen of the United States, residing at Jersey City, in the county of Hudson and State of New Jersey, have invented certain new and useful Improvements in Water-Tube Boilers, of which the following is a specification.

My invention relates to water tube boilers and has for its object an increase of efficiency and capacity in installations of large units. This object is accomplished by combining two units each comprising a bank of inclined water tubes arranged symmetrically above a common fuel and combustion chamber, the fuel chamber extending from one side of the boiler to the other to provide a large furnace volume, and the heating surfaces of the units disposed relative 15 to each other so as to form an A-shaped combustion chamber which shall be open to the escape of the products of combustion, over the tubes of the heating surface, along the upper portions of the inclined sides of the 20 combustion chamber.

The invention will be understood by reference to the accompanying drawings in which—

Figure 1 is a longitudinal section; and 30 Fig. 2, a detail view of the means for protecting the lower ends of the upper headers.

In Fig. 1, I have shown two units each comprising a bank of inclined water tubes, the tubes 1 of the left hand unit being expanded into lower and upper headers 2 and 3, and the tubes 4 of the right hand unit being expanded into lower and upper headers 5 and 6. These headers extend transversely of the boiler from one side wall of the setting to the other side wall. Each bank is divided by transverse baffles 7 and 8, the baffles 7 rising from baffles 9 extending from the front headers toward the rear, thus providing a plurality of transverse passes for 40 the products of combustion across and around the tubes as indicated by the arrows.

The upper headers 3 are connected, by substantially horizontal separator tubes 10, with a steam and water drum 11, and the latter is connected with the lower headers 2 by downcomers 12. The upper headers 6 are connected, by substantially horizontal separator tubes 13, with a steam and water drum 14, and the latter is connected with

the lower headers 5 by downcomers 15. 55 Walls 8' extend from the transverse baffles 8 to the steam and water drums 11 and 14, and in the space between these walls and the roof of the setting above the banks of tubes, and above the first and second passes, 60 are placed superheaters 16 and 17 of any approved type. The form shown comprises two transverse boxes connected by upwardly extending U-shaped tubes. The upper box of each superheater is connected to the steam 65 space of the corresponding drum.

The boiler units above described are suspended over a common furnace extending from the front to the rear of the boiler. In the design shown the furnace is divided 70 along its center by a low wall 18 extending from one side wall to the other. This wall serves as a rear wall for the two fuel bed sections, in this instance two chain grate stokers 19 and 20 of any approved construction, and operated independently of each other, one from the front and the other from the rear of the setting. The mud drums of the boilers are connected to the lower headers, and are shown outside of the ignition 75 arches 21 and 22, where they are protected from the heat of the furnace. The headers 3 and 6 extend to the roof of the setting thereby forming a closed space between said headers and the section of the roof included 80 between them.

The two boiler units are so disposed relative to each other that the upper headers 3 and 6 converge toward each other downwardly and their lower ends meet approximately at the transverse central vertical plane of the setting. There is thus provided a large A-shaped combustion chamber 85 open to the escape of the products of combustion along the upper portions of the inclined sides, that is, at the uptake ends of the inclined tubes. The gases from the combustion chamber divide and pass over the heating surfaces of the units, as indicated by the arrows, to the flue outlets 24 90 and 25 on the respective sides of the units. In this design the water circulation in the two units is independent, it being upwardly through the inclined tubes to the upper headers, separator tubes 10 and 13, drums 11 and 14, downcomers 12 and 15 to the lower headers. The substantially horizontal separator tubes 10 and 13 are an im- 95 100 105

portant feature of the arrangement as the steam is separated from the water in flowing through them and additional disengaging surface is thus obtained. The steam is led from the front and rear drums 11 and 14 through the superheaters to the mains, although mains may be provided for the delivery of saturated steam directly from the drums 11 and 14.

10 It may be desirable to connect the water boxes 26 below the wall 18 with the circulation. For such purpose I have shown them connected by pipes 27 and 28 with the lower and upper headers.

15 The coal is fired at the front and rear of the boiler setting, and with the arrangement described the character of the combustion may be maintained substantially constant from one side of the boiler to the other, and the loss often experienced through a stream or lane of excess air or unconsumed combustible gases passing through the boiler and escaping to the stacks will be avoided. It is well-known

20 among engineers that in ordinary boiler furnaces there is a great variation in analyses taken from different points in the path of the flue gases leaving the furnace, whereas with the present furnace arrangement this action is reduced to a minimum, as any irregularity from the front to the rear of the grates disappears before the gases pass from the upper part of the combustion chamber, and as the composition of 25 the gases for uniform firing conditions will be uniform from one side of the boiler to the other, it follows that the composition of the entire volume of the gases leaving the furnace will be substantially uniform.

30 40 The angle of inclination of the tubes of the heating surfaces is approximately 45° to the horizontal, and the planes of the rear headers approximately at an angle of 90° to each other. I do not, however, restrict

45 myself to these angles, the essential feature being the disposition of the units relative to each other over a common furnace and combustion chamber to provide an A-shaped combustion chamber of relatively large 50 volume, and the other features herein described, which contribute to an increased efficiency and economy in operation.

It is necessary in the practical operation 55 of the boiler to protect the lower ends of the upper headers from the radiant heat of the fire, otherwise these ends would burn out on account of the accumulation of sediment inside of them. For this purpose I have shown a special tile 30 held up by iron 60 rods or bolts 31 passing through holes in the tile, the rods or bolts being attached to a suspension member 32 which rests on cross members 33. The lowermost ends of the rods or bolts are protected by means of fire 65 clay, or other material, which is introduced

in a plastic state into holes or recesses provided in the tile. In addition to the protection afforded by the suspended tile, I encircle the upper ends of the lowermost generating tubes by tiles 34, held in place 70 by suitable clamps 35; or the suspended tile 30 could be constructed in such way as to engage with and hold the tiles 34 in place.

What I claim is:

1. In a water tube boiler, the combination of two units each comprising a bank of inclined water tubes, upper and lower headers into which said tubes are expanded, said units being so disposed that the upper headers converge toward each other downwardly and extend upwardly to the roof of the setting, whereby there is formed a centrally disposed A-shaped combustion chamber between the units, a steam and water drum for 80 each unit, substantially horizontal separator tubes connecting the upper ends of the upper headers to the corresponding steam and water drum, downcomers connecting said drums to the lower headers, and walls in 85 front of said downcomers and extending from the steam and water drums to the banks of tubes.

2. In a water tube boiler, the combination of two units each comprising a bank of inclined water tubes, upper and lower headers into which said tubes are expanded, said units being so disposed that the upper headers converge toward each other downwardly, whereby there is formed a centrally disposed 90 A-shaped combustion chamber between the units, a steam and water drum for each unit, substantially horizontal separator tubes connecting the upper ends of the upper headers to the corresponding steam and water 95 drum, downcomers connecting said drums to the lower headers, transverse baffles dividing the banks of tubes into a plurality of passes beginning at the steam uptake end, walls extending from the lower transverse baffles to 100 the steam and water drums, a superheater in the space above each bank of tubes, and pipes connecting said superheaters with the steam space of the corresponding drum.

3. In a water tube boiler, the combination of two units each comprising a bank of inclined water tubes, upper and lower headers into which said tubes are expanded, said units being so disposed that the upper headers converge toward each other downwardly, whereby there is formed a centrally disposed A-shaped combustion chamber between the units, a steam and water drum for 115 each unit, substantially horizontal separator tubes connecting the upper ends of the upper headers to the corresponding steam and water drum, downcomers connecting said drums to the lower headers, a centrally disposed fuel chamber, a wall dividing said chamber along its center, water boxes below 120 125 130

said wall, and pipes connecting said boxes with the upper and lower headers of each unit.

4. In a water tube boiler, the combination 5 of two units each comprising a bank of inclined water tubes, upper and lower headers into which said tubes are expanded, said units being so disposed that the upper headers converge toward each other downwardly, 10 whereby there is formed a centrally disposed A-shaped combustion chamber between the units, a refractory tile placed at the uppermost part of the combustion chamber to protect the lower ends of the upper headers, bolts passing through said tile, and a suspension member to which said bolts are 35 attached.

5. In a water tube boiler, the combination 15 of two units each comprising a bank of inclined water tubes, upper and lower headers into which said tubes are expanded, said units being so disposed that the upper headers converge toward each other downwardly, 20 whereby there is formed a centrally disposed A-shaped combustion chamber between the units, a refractory tile to protect the lower ends of the upper headers, a steam and water drum for each unit, tubes connecting the upper ends of the upper headers to 25 said drums, and downcomers connecting said drums to the lower headers.

6. In a water tube boiler, the combination 30 of two units each comprising a bank of inclined water tubes, upper and lower head-

ers into which said tubes are expanded, said units being so disposed that the upper headers converge toward each other downwardly, whereby there is formed a centrally disposed A-shaped combustion chamber be- 35 tween the units, a refractory tile placed at the uppermost part of the combustion chamber to protect the lower ends of the upper headers, bolts passing through said tile, and a suspension member to which said bolts are 40 attached.

7. In a water tube boiler, the combination 45 of two units each comprising a bank of inclined water tubes, upper and lower headers into which said tubes are expanded, said units being so disposed that the upper headers converge toward each other downwardly, whereby there is formed a centrally disposed A-shaped combustion chamber between the units, a refractory tile to protect the lower 50 ends of the upper headers, and tiles encircling the upper ends of the lowermost tubes.

In testimony whereof I have hereunto signed my name in the presence of two subscribing witnesses.

DAVID S. JACOBUS.
